BRIEF CASE FRAMES

Lewis Lifton, New York, N. Y.

Application December 27, 1956, Serial No. 630,983

7 Claims. (Cl. 150—29)

2

Fig. 8 is a vertical sectional view on the line 8—8 of Fig. 7.

Fig. 9 is an exploded and fragmentary perspective view of the swiveled frames shown in Fig. 1.

5 Fig. 10 is a view similar to Fig. 1 but illustrating another protector according to my invention.

Fig. 11 is a front view of the protector shown in Fig. 10.

Fig. 12 is a rear view of Fig. 11.

10 Fig. 13 is a top view of Fig. 12.

Fig. 14 is a bottom view of Fig. 12.

Fig. 15 is a side view of Fig. 12.

Fig. 16 is a fragmentary exploded perspective view of the pivoted frames illustrated in Fig. 10.

15 Fig. 17 is an enlarged horizontal view on the line 17—17 of Fig. 10.

Fig. 18 is a sectional view on the line 18—18 of Fig. 17.

20 Fig. 19 is a view similar to Fig. 9 illustrating another form according to the invention.

Fig. 20 is an assembled view of the parts shown in Fig. 19.

Fig. 21 is a horizontal sectional view on the line 21—21 of Fig. 20, and

25 Fig. 22 is an enlarged sectional view on the line 22—22 of Fig. 21.

Illustrative of the embodiments disclosed, swingable appropriately covered complementary inner and outer frame sections FA and FB characterize mouth M of a conventional brief case (not shown).

As to sections FA and FB each comprises an inverted U-shaped metal bar generally denoted 10 embodying a horizontal reach 11 provided with spaced depending legs 12.

30 35 Bars 10 are concealed and adhesively secured within a respective covering C which may be of leather or a simulation thereof.

The terminals or ends of legs 12 include aligned perforations 13, in alignment with perforations 14 of respective coverings C. The aligned perforations at the covered terminals of sections FA and FB are adapted to receive shanks S of rivet or fulcrum means R as is well understood.

40 45 Inner frame section FA is smaller in size than outer frame section FB and may be swung into or out of the latter to fully close or open mouth M. Coverings C extend beyond lower terminals of legs 12 and end in lips L (Fig. 9).

50 55 In actual practice, lips L are adhesively secured to each other and end faces 100 of these lips, if unprotected are exposed. During use these lips L do at times separate thereby exposing the metal depending legs 12 permitting moisture to attack the latter and causing oxidation or rusting.

55 60 Unintentional blows received by the lower parts of the outer frame section FB during use also cause scratching, scraping and marring of end faces 100 and as previously stated cause even separation of lips L. In either case the appearance of the brief case is disadvantageously affected.

To overcome such disadvantages particularly in regard to shielding the lower covered terminals or ends of the outer frame section FB and end faces 100, hollow protectors or keepers, broadly denoted, P are provided to receive such lowered covered terminals.

65 70 Each frame protector P according to the embodiment illustrated in Figs. 1—9 comprises an open top housing having an uninterrupted bottom wall 15 from which extends front and rear walls 16 and 17 as well as the side walls 18. Bottom wall 15 and sides 18 constitute a rim defining with front wall 16 a receptacle characterizing a

socket or opening 19 for receiving the lower covered

My invention relates to brief case frames comprising complementary inverted and covered U-shaped inner and outer frames adapted to form the mouth of the brief case and adapted to be swingably brought together or widely swung apart in the matter of closing or opening the brief case. In actual practice the inner and outer U-shaped frames each includes a reach having spaced depending legs. The frames embody an appropriate leather covering or simulation thereof. The lower or inner portions of corresponding legs of the inner and outer frames are pivotally mounted on a cylindrical shank of a rivet. Heretofore a metal washer was mounted on each rivet between corresponding legs of the frames and another metal washer was mounted on each rivet and positioned against outside legs of the frames before the respective rivet or fulcrum means for the corresponding legs was upset. By such arrangement although the frames are pivotally associated, the lower faces of the spaced depending legs of the covering of the outer frame are thus exposed. Such exposed faces leave an unsightly appearance particularly after use of the brief case when such covering at such exposed faces start to separate. If the covering at the exposed faces to separate the metal frames become uncovered and unattractively show, hence detracting from the desired appearance of the brief case apart from the fact that moisture or the like now also attacks the metal frames at the exposed areas. In addition, the lower faces of the separated covering often becomes scraped and often frays thereby further detracting from the desired appearance. The invention accordingly aims to provide a novel protector adapted to receive and conceal the lower ends of the depending legs of the outer covered frame to preclude exposure of the end faces of the covering thereof. Another object is realized in the provision of a protector of the character referred to which actually serves to enhance the appearance of the brief case. Another important object resides in the provision of a multi-purpose one piece protector also having bearing means eliminating the need of interposing separate washers between the lower corresponding depending legs of the inner and outer complementary frames. Other important aspects, objects, and structural and functional features of the invention will be considered in the following detailed specification considered in the light of the accompanying drawings wherein:

Fig. 1 is a perspective view of the covered inner and outer complementary pivoted frames, shown partly broken away and also exhibiting the protector according to the preferred embodiment of my invention.

Fig. 2 is a front view of the protector illustrated in Fig. 1.

Fig. 3 is a rear view of Fig. 2.

Fig. 4 is a side view of Fig. 2.

Fig. 5 is a top view of Fig. 3.

Fig. 6 is a bottom view of Fig. 3.

Fig. 7 is an enlarged horizontal sectional view on the line 7—7 of Fig. 1.

terminals or ends of frame section FB. As to walls 16 and 17 of the protectors P, each includes aligned openings 20 and 21 for reception of cylindrical fulcrum shank S of rivet R. After threading shank S through perforations 14, 13 and 14 (Fig. 7) of frame section FA and through aligned openings or perforations 21, 14, 13, 14, 20, in frame section FB and protector P, shank S has its outer end 22 upset whereby the latter and head H of rivet R rotatably retain frame sections FA and FB on fulcrum shanks S.

Rear wall 17 of each protector P although in part detached from sides 18 (Fig. 9) characterizes a bearing against which section FA swivels or rotates. It follows that protectors P apart from preventing fraying, scraping and even separation of lips L, further serve to facilitate rotation of section FA relative to section FB and vice versa. It is also apparent that the rims of protectors P also shield the juxtaposed end faces 100 of covering C of the outer frame section FB. It will be observed that leather coverings C of frame sections FA and FB terminate in margins 25 to which are appropriately attached for example, by stitching, gusset portions and front and rear walls of the brief case (not shown).

In the embodiment according to Figs. 10 to 18 parts corresponding to the form illustrated in Figs. 1-9 are primed. However protector P' according to Figs. 10-18 distinguishes from the form illustrated in Figs. 1-9 in that rim RM constituting the bottom and side walls is uninterrupted. In Figs. 10 to 18, rim RM is also more rounded. Otherwise the embodiment according to Figs. 10 to 18 is along the lines of the form shown in Figs. 1 to 9.

In the modification shown in Figs. 19 to 21, parts corresponding to the embodiment illustrated in Figs. 10 to 18, have been double primed and socket 19" of protector P" is now bounded by rim RM" and front wall 16", the bearing plate or back wall 17 of the type shown in Figs. 10 to 18 having been removed. Instead a conventional and separate bearing washer or annulus W is employed on shank S" and interposed between the complementary inner and outer covered frame sections FA" and FB". In other aspects the embodiment according to Figs. 19 to 21 follows the forms shown in Figs. 1 to 18.

Various changes may be made in details of construction and arrangement of parts without departing from the scope of the invention or sacrificing any of the advantages thereof inherent therein.

I claim:

1. In a hollow protector for shielding juxtaposed end faces of a covered terminal of a depending leg of a frame section; the combination of, a front wall, and a rim carried by said front wall and defining therewith a socket for reception of said covered terminal, and said rim comprising an uninterrupted bottom wall to shield said end faces.

2. In a hollow protector for shielding juxtaposed end faces of a covered terminal of a depending leg of a frame section; the combination of, a front wall, a rim carried by said front wall and defining therewith a socket for reception of said covered terminal and said rim comprising an uninterrupted bottom wall to shield said end faces.

faces, and means to hold said terminal within said socket.

3. In a hollow protector for shielding juxtaposed end faces of a covered terminal of depending legs of a frame section; the combination of, a front wall, a rim carried by said front wall and defining therewith a socket for reception of said covered terminal to permit said rim to shield said end faces, and a rear wall carried by said rim and spaced from said front wall and in part defining said socket.

10 4. In a hollow protector for shielding juxtaposed end faces of a covered and perforated terminal of a depending leg of a frame section and for cooperating with a rivet having a shank adapted to be received by said terminal; the combination of, a front wall, a rim carried by said front wall and defining therewith a socket for reception of said covered terminal to permit said rim to shield said end faces, and a bearing carried by said rim and spaced from said front wall and in part defining said socket, said front wall and bearing having aligned perforations for reception of said shank to retain said perforated terminal within said protector.

25 5. In a hollow protector for shielding juxtaposed end faces of a covered terminal of a depending leg of a frame section; the combination of, a front wall, and a rim carried by said front wall and comprising spaced sides and an uninterrupted bottom wall defining with said front wall a socket for reception of said covered terminal to permit said sides and bottom wall to shield said end faces.

30 6. In a hollow protector for shielding juxtaposed end faces of a covered terminal of a depending leg of a frame section; the combination of, a front wall, a rim carried by said front wall and comprising spaced sides and a bottom wall defining with said front wall a socket for reception of said covered terminal to permit said sides and bottom wall to shield said end faces, and a rear wall spaced from and substantially parallel to said front wall and integral with said rim.

40 7. In a hollow protector for shielding juxtaposed end faces of a covered and perforated terminal of a depending leg of a frame section; the combination of, a front wall, a rim carried by said front wall and comprising spaced sides and a bottom wall defining with said front wall a socket for reception of said covered terminal to permit said sides and bottom wall to shield said end faces, and a bearing comprising a rear wall extending from said rim and spaced from and substantially parallel to said front wall and in part defining said socket, said front wall and rear wall having aligned perforations for reception of said shank to retain said perforated terminal within said protector.
